US0D1035353S

(12) **United States Design Patent** (10) Patent No.: **US D1,035,353 S**
(45) Date of Patent: ** Jul. 16, 2024

(54) **LEG FRAME ASSEMBLY FOR COT**

(71) Applicant: **JKL CORPORATION**, Seoul (KR)

(72) Inventor: **Jeh Kun Lah**, Seoul (KR)

(**) Term: **15 Years**

(21) Appl. No.: **35/518,051**

(22) Filed: **Jul. 14, 2023**

(80) **Hague Agreement Data**

Int. Filing Date: **Jul. 14, 2023**

Int. Reg. No.: **DM/230627**

Int. Reg. Date: **Jul. 14, 2023**

Int. Reg. Pub. Date: **Aug. 11, 2023**

(30) **Foreign Application Priority Data**

Jan. 18, 2023 (KR) 30-2023-0002125

(51) **LOC (14) Cl.** **06-06**

Primary Examiner — Richard Edgar

Assistant Examiner — Jessica Ruth Grable

(57) **CLAIM**

The ornamental design for a leg frame assembly for cot, as shown and described.

DESCRIPTION

1. Leg frame assembly for cot

1.1 : Perspective

1.2 : Front

1.3 : Back

1.4 : Left

1.5 : Right

1.6 : Top

1.7 : Bottom

1. Title of the design: Leg frame assembly for cot; 2. Use of the design: used for supporting a seat member of a cot by being coupled to the seat member; 3. Distinctive points: shape of the product as shown; 4. View best showing the design: Fig. 1.1.

1 Claim, 7 Drawing Sheets
